EDWARD FRANK MILLS, OF LYNN, AND LAWRENCE HOWES TEEL, OF SALEM, MASSACHUSETTS, ASSIGNEES TO A. SCHRADER'S SON, INC., OF BROOKLYN, NEW YORK, A CORPORATION OF NEW YORK.

APPARATUS FOR AUTOMATICALLY CONTROLLING THE OPERATION OF AIR-PUMPS.

1,366,204.

Specification of Letters Patent. Patented Jan. 18, 1921.

Application filed January 4, 1916. Serial No. 70,295.

To all whom it may concern:

Be it known that we, EDWARD F. MILLS and LAWRENCE H. TEEL, citizens of the United States, and residents of Lynn and Salem, respectively, in the county of Essex and State of Massachusetts, have invented an Improvement in Apparatus for Automatically Controlling the Operation of Air-Pumps, of which the following description, 10 in connection with the accompanying drawings, is a specification, like characters on the drawings representing like parts.

This invention relates to apparatus for automatically controlling the operation of an air pump when the pressure in the discharge side of the system in which the pump is used, reaches a predetermined point.

The invention is especially adapted among other uses to be employed in garages and 20 like places, in which a power-driven air pump is employed for supplying air pressure to the tires of automobiles.

The invention has for its object to provide a simple and efficient means for automatically stopping the action of the pump without stopping the prime mover therefor, when the pressure in the automobile tire or other air receptacle connected with the discharge side of the pump, reaches a predetermined amount.

To this end we employ between the pump and the prime mover a transmitting mechanism, which has a movable member, and provide means for moving said member so as to disconnect the pump from the prime mover, and make said means responsive to a predetermined pressure created by the pump. Provision is made for locking said movable member in its operative position, 40 which locking means is operated to release said movable member when the pressure reaches a predetermined amount.

Provision may also be made for retaining the movable member in its inoperative position until positively restored to its operative position.

Provision may also be made for sounding an audible signal when the movable member of the power-transmitting mechanism is 50 moved to render the prime mover ineffective upon the pump.

These and other features of this invention will be pointed out in the claim at the end of this specification.

Figure 1 is a front elevation of one form 55 of apparatus embodying this invention.

Fig. 2, a section on the line 2—2, Fig. 1, looking toward the right, with parts broken away.

Figs. 3 and 4, diagrammatic views to illustrate the working of the apparatus, and

Fig. 5, an enlarged section of the pressure-responsive device to be referred to.

Referring to the drawing *a* represents an air pump of usual or known construction, 65 and *b* a prime mover therefor, which is shown as an electric motor of known construction. The pump *a* is operatively connected with the motor *b* to be driven thereby by a transmitting mechanism, which is herein shown as consisting of a pinion 10 on the armature shaft 12 of the motor *b*, a gear 13 on the pump shaft 14 and an intermediate pinion 15, which is designed to be engaged with and disengaged from the pinion 10 70 and gear 13 and constitutes the movable member of the transmitting mechanism between the motor *b* and the pump *a*.

In the present instance, the pinion 15 is mounted on the long arm 16 of an elbow 80 lever 17, which is loosely mounted on the pump shaft 14 and has its short arm 18 connected by a link 19 with a lever 20, pivoted at 21 and having its free end coöperating with a lever 22, which may and preferably 85 will be provided with notches 23, 24, (see Figs. 3 and 4) for the reception of the free end of the lever 20, for a purpose as will be described.

The lever 22 is pivoted at 25 and has its 90 short arm 26 normally held by a spring 27 against a device which is responsive to a predetermined air pressure in the discharge side of the system in which the pump *a* is included, which discharge side is represented as a pipe 28.

The pressure-responsive device herein shown consists of a piston 30 (see Fig. 5) located in a cylinder 31, which is in open communication at one end with the discharge pipe 28 of the pump, and has its other end forming a seat for a flange 32 on the piston, which latter is normally held to its seat by a coiled spring 33 having its lower end secured to a collar 34, fitted on the 105 reduced end of the rod 36 of said piston, and having its upper end secured to a collar 37 loose on the piston rod and connected by

pins 38 with a collar 40, which is slidable on the outside of a cylindrical casing or tube 41, attached at its upper end to the cylinder 31 and provided with longitudinally extended slots 42 through which the pins 38 are extended. The collar 40 is held by the contraction of the spring 33 against a collar 44 in threaded engagement with the casing 41. The spring 33 is normally contracted and holds the collar 40 against the collar 44 and also holds the piston 30 to its seat.

The piston rod 36 is extended through the head 45 of the casing 41 and bears against the short arm 26 of the lever 22. By adjusting the collar 44 on the casing 41, the spring 33 can be regulated to hold the piston 30 against its seat while the pressure in the discharge pipe 28 and cylinder 31 remains below a predetermined amount. When however, the pressure reaches the predetermined amount, the piston 30 is moved in the direction of the arrow 47, Fig. 5, and the rod 36 acts on the arm 26 of the lever 22 against the action of the spring 27 and turns said lever on its pivot until the lever 20 is released, whereupon the weight of the short arm 18 of the elbow lever 17, assisted it may be by a counter-weight or spring, not shown, but in a manner well understood, turns the elbow lever and moves the pinion 15 out of engagement with the pinion 10 and from the position indicated in Fig. 3 to that indicated in Fig. 4, thereby mechanically interrupting the transmission of power from the prime mover *b* to the pump *a*; and consequently stopping the pump.

When the movable member 15 of the transmitting mechanism has been moved into its inoperative position shown in Fig. 4, it is preferred to lock or hold it in this position until it is manually restored to its operative position, which may be accomplished by providing the lever 22 with the notch 24 into which the lever 20 is designed to enter, as represented in Fig. 4. The lever 22 may have attached to it a bell 52, which is designed to be struck by the lever 20 and thus give an audible signal that the predetermined pressure has been reached.

The apparatus among other uses, is especially adapted to be employed in garages for pumping up tires of automobiles, in which case the operator adjusts the pressure device to respond to a given or predetermined pressure, as, for instance, eighty pounds, and then connects the tire to be inflated with the discharge pipe 28 of the pump, through a flexible tube or hose, not shown, in a manner

well understood. When the tire has been properly connected with the pump, the operator turns the lever 20 until it engages the notch 23 in the lever 22, which action brings the pinion 15 into mesh with the pinion 10 and starts the pump in operation. If desired, the operator can leave the apparatus, and the pump will continue in operation until the air pressure in the tire reaches eighty pounds, whereupon the pressure-responsive device trips the locking lever 22 and permits the movable member 15 to be moved into its inoperative position shown in Fig. 4, and thereby mechanically disconnect the pump *a* from the motor *b* and stop the pump without stopping the motor, which latter can continue to run if desired. When the pressure responsive device operates, as described, the bell 52 is struck and the operator is notified that the tire has been supplied with the desired air pressure.

In the present instance, we have illustrated one form of mechanism for transmitting power from the prime mover to the pump, but it is not desired to limit the invention in this respect.

So also, we have shown one form of prime mover, which may be stationary or portable, but it is not desired to limit the invention in this respect.

Claim:

In an apparatus of the character described, in combination, an air pump, a prime mover therefor, a transmitting mechanism between the said pump and prime mover provided with a movable member capable of rendering the prime mover ineffective upon the pump, a lever carrying said movable member, a latching lever, means for connecting said levers, a locking lever co-operating with said latching lever, a piston co-operating with said locking lever, a cylinder in which said piston is located and communicating with the discharge side of the pump, a spring acting on said piston in opposition to the air pressure in said cylinder and responsive to said pressure when the latter reaches a predetermined amount to permit said piston to disengage said locking lever from said latching lever and permit the lever carrying the movable member to be turned and move said movable member into its inoperative position.

In testimony whereof we have signed our names to this specification.

EDWARD FRANK MILLS.
LAWRENCE HOWES TEEL.
